ATTORNEY

UNITED STATES PATENT OFFICE.

SYLVIA SUIBLEY ROBERTSON, OF CLEAR LAKE, IOWA.

DESIGN FOR A DRESS OR FROCK.

57,727.

Specification for Design. Patented Apr. 26, 1921.

Application filed August 23, 1920. Serial No. 405,514. Term of patent 14 years.

To all whom it may concern:

Be it known that I, SYLVIA SUIBLEY ROBERTSON, a citizen of the United States, residing at Clear Lake, in the county of Cerro Gordo and State of Iowa, have invented a new, original, and ornamental Design for a Dress or Frock, of which the following is a specification, reference being had to the accompanying drawings, forming a part thereof.

Fig. 2 is a rear view thereof.

I claim:

The ornamental design for a dress or frock as shown.

SYLVIA SUIBLEY ROBERTSON.
